UNITED STATES PATENT OFFICE.

BENNO VOM EIGEN, OF NEWARK, NEW JERSEY, ASSIGNOR TO AUG. GOERTZ & CO., OF SAME PLACE.

PURSE OR BAG FRAME.

SPECIFICATION forming part of Letters Patent No. 625,028, dated May 16, 1899.

Application filed March 2, 1899. Serial No. 707,491. (No model.)

To all whom it may concern:

Be it known that I, BENNO VOM EIGEN, a citizen of the United States, residing at Newark, in the county of Essex and State of New Jersey, have invented certain new and useful Improvements in Purse or Bag Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to improvements in metallic frames for purses, bags, and the like; and the invention relates more particularly to a novel construction of frame and locking or holding catch connected with the frame-sections thereof and mechanism for operating the same comprising several independently-actuated parts, all of which are combined to finally release the holding-jaw and locking-catch of the hinged frame-sections.

The main purpose of this invention is to provide a purse or bag frame and its latch or catch which shall be neat in appearance and shall be of a simple, strong, and durable construction, the parts being arranged with a view of furnishing what may be termed a "trick" or "puzzle" frame, which will offer abundant opportunities to exercise good judgment in manipulating the parts of the same and at the same time afford great amusement.

The invention therefore consists in the novel construction of purse or bag frame and its holding or locking catch, as well as in the novel arrangements and combinations of the parts thereof, all of which will be described in detail in the following specification and finally embodied in the clauses of the claim.

The invention is clearly illustrated in the accompanying drawings, in which--

Figure 1 is a front or side view of a purse or bag frame embodying the principles of this invention, said view representing either side of the frame, since both sides look alike; and Fig. 2 is a plan or top view of the frame. Fig. 3 is a bottom view of the frame with a pair of inlays removed to clearly illustrate the in-

ner arrangement of the frame-sections and the operating mechanism connected therewith. Fig. 4 is a longitudinal vertical section of the upper portion of the purse or bag frame, taken on line x in Fig. 3 when looking in the direction of arrow x' in said figure, said view representing all the parts of the operating mechanism in their normally locked or holding positions. Fig. 5 is a view similar to Fig. 4, showing a portion of the operating mechanism in its operated or disengaged position to illustrate the first step for unlocking or releasing the holding-catch of the frame. Fig. 6 is a longitudinal section of the upper portion of the purse or bag frame, taken on line x^2 in Fig. 3, but looking in the direction of arrow x^3 in said figure, said view representing in dotted outline the arrangement of a pivoted operating-lever on the outer side of the frame-section and a stud or post connected therewith, which normally is in holding engagement with the locking or holding catch, said view also indicating in dotted outline the position of said operating-lever and its stud or post to illustrate the second step for permitting the final unlocking or releasing of the holding-catch of the frame. Fig. 7 is a vertical cross-section taken on line y in Fig. 3, looking in the direction of arrow y' ; and Fig. 8 is a cross-section taken on line z in said Fig. 3, looking in the direction of arrow z' . Fig. 9 is a perspective view of the spring-catch and finger-piece and also of the holding-jaw for engaging the said catch, and Fig. 10 is a perspective view of the inlays to be used in connection with the frame.

Similar letters of reference are employed in all of the said above-described views to indicate corresponding parts.

In said drawings, a and a' indicate a pair of frame-sections which are pivotally connected at their lower end portions a^2 by means of suitable pins or rivets b and are spring-actuated by means of a spring b' , substantially as illustrated in Fig. 1, or the said parts may be pivotally connected with each other in any other well-known manner. Said frame-sections a and a' are respectively provided with inwardly-extending sides a^3 and a^4 , as will be noticed from the several figures of the draw-

ings, and in which there is an arrangement of perforations a^5 for properly securing in position, by means of the rivets or pins c^2 in the frame-section a , an inlay c , and by means 5 of rivets or pins c^3 is secured in the frame-section a' an inlay c' , said pins or rivets being arranged in said perforations a^5 in the frame-sections and in correspondingly-placed perforations c^4 in the body of said inlays and also 10 in the leg portions c^5 thereof, whereby the material g of the bag or purse is securely held in its proper position against the inner sides of the parts a^3 and a^4 of the respective frame-sections, as clearly illustrated in Figs. 7 and 15 8. As will be seen from said Figs. 7 and 8, the inlay c is formed with a shoulder c^6 and an upwardly-extending portion c^7 , having lugs c^8 or the like projecting from the side thereof, substantially as shown in Fig. 10, 20 whereby the upper portion of said inlay c when arranged in position in the frame-section a forms, with the said section, a suitable chamber C . The inlay c' is also provided with a shoulder c^9 and an upwardly-extending portion c^{10} , whereby said portion when 25 arranged in position in the frame-section a' forms, with the said section, a suitable chamber C' . Said inlay is provided with suitably-formed openings c^{11} and c^{12} , and the inlay c' is 30 also provided with similar openings c^{13} and c^{14} , said openings when the two inlays are secured in position against the inner surfaces of the frame-sections being directly opposite each other, as will be clearly seen from an 35 inspection of Figs. 7 and 10.

Secured in position upon the upper surface of the frame-section a is a suitably-constructed ornamental shell d , which is preferably made $\square$ shape in cross-section, so as 40 to form a channel-bar having the open ends d^1 and d^2 , as clearly illustrated in Figs. 4 and 5. The sides of said channel-bar are provided with suitable tongues or lugs d^3 , which are passed through slots a^6 in the frame-section 45 a and are bent over against the under side thereof to secure said bar d in a central position on said frame-section; but of course it will be evident that any other known fastening means may be employed for securing said 50 bar in place upon the frame-section a . Within said channel-bar d is loosely arranged a coiled spring f , the ends of which are in operative contact with the ends of suitably-constructed push-pieces h and h' , which are slidably arranged upon the upper surface of the frame-section a and have their respective ends h^2 and h^3 extending into the respective open ends d^1 and d^2 of said bar d and abutting against the ends of the spring f , as above 55 stated. The said push-pieces h and h' are preferably made as indicated in Fig. 9, each piece comprising a metallic shell h^4 , in which I have secured in any desirable manner a block h^5 , provided with the offsets h^6 and a 60 post h^7 . The said post h^7 of the push-piece h is passed through a slot in the upper surface of the frame-section a and then fitted in

a hole i , formed in a slide i , said slide being provided with a lip i^2 , formed at a right angle thereto, or approximately so, and the said post h^7 being clenched on the inner side of said slide i , the said slide and said piece h thus being arranged on the inner and outer sides of the frame-section, as will be clearly evident from an inspection of Figs. 4 and 5. The other push-piece h' has its post h^7 likewise passed through a slot in the upper surface of the frame-section a and is then fitted in a hole e' , formed in the catch-plate e . Said plate e is preferably curved, as at e^2 , and is provided with a spring-arm e^3 , bent, as at e^4 , to form a holding-tongue e^5 , substantially as illustrated. Said plate e is also provided with a pair of downwardly-extending flanges e^6 and e^7 . The frame-section a' is provided with an inwardly-projecting arm a^8 , which extends through the openings c^{14} and c^{12} in the respective inlays c' and c and into the chamber C , having a hook end a^9 , which can be forced in operative holding engagement with the edge e^8 of the said holding-tongue e^5 when the two frame-sections a and a' are closed upon each other. It will thus be evident that the construction and arrangement of the several parts, so far as described, will form a suitable lock construction for 95 purse or bag frames, the catch being released by pushing the piece h' toward the spring f and the parts being brought into their holding relation by simply closing the frame-sections a and a' . 100

In addition to the above I have provided the frame-sections with a peculiarly-arranged locking mechanism to prevent the catch-plate e being operated unless said locking mechanism is first properly manipulated. 105

As will be seen from the several figures of the drawings, I have secured in a central perforation in the side a^3 of the frame-section a a pin or post a^8 , on which I have pivotally arranged a lever k , (see more particularly Fig. 1, 110) said lever having its arm portions k^1 and k^2 extending on opposite sides of this fulcrum support, substantially as illustrated. The said arm portion k^1 has secured thereto in any well-known manner a post k^3 , which 115 extends through a slot or opening a^{13} in the side a^3 of the frame-section a and normally is arranged beneath the edge i^3 of the lip i^2 of the slide i , as clearly illustrated in Figs. 3, 4, and 8. The arm portion k^2 is likewise provided 120 with a post k^4 , which extends through a slot or opening a^9 in the side of the frame-section a and normally is arranged directly in front of the edge e^8 of the flange e^7 of the catch-plate e to hold said plate in its immovable or locked 125 position, as will be clearly evident from an inspection of Figs. 3 and 4. Against the opposite side of the bag or purse frame I have pivotally arranged on a pin or post a^{10} , secured in a central perforation in the side a^4 of the frame-section a' , a similarly-constructed lever l , which is provided with arm portions l^1 and l^2 , 130 extending on opposite sides of this fulcrum support a^{10} . The arm portion l^1 is provided on

that side nearest the part a^4 of the frame-section a' with a stud l^3 , which is preferably made pointed, as indicated in Fig. 8, and can be made to slide over a serrated or corrugated surface a^{11} in the side a^4 of said frame-section. The other arm portion l^2 of said lever l has a post l^4 , which extends through an opening a^{12} in the side a^4 of the frame-section a' and normally is arranged directly in front of the edge e^{10} of the flange e^6 of the catch-plate e , whereby the sliding movement of said plate e is prevented, although the lever k may have been previously operated and its post k^4 disengaged.

Having described the arrangement and construction of the several parts of the operating mechanism, I will now endeavor to give a brief description of operating the several parts in order to release the catch-plate e to permit the pivotal separation of the frame-sections a and a' .

The operation is as follows: I first push the piece h in the direction of the arrows 1 in Figs. 4 and 5 against the end of the spring f , whereby the edge i^3 of the lip i^2 of the plate i is moved away from the post k^3 of the arm portion k' . While still holding said push-piece h in its operated position, by means of another finger I apply pressure to the under edge of the arm portion k' of the lever k , whereby said post k^3 is forced upwardly along the edge i^4 of said lip i^2 , as indicated in Fig. 5, and said plate will be retained in its operative position. Thus it will be seen that the purpose of said plate i in its initial position is to prevent the manipulation of the lever k , but permit said lever to be actuated when said plate is pushed forward by means of the piece h . At the same time that the arm portion k' moves in an upward direction the other arm portion k^2 of the lever k will move downwardly and disengage the post k^4 from contact with the edge e^9 of the flange e^7 of the catch-plate e . Pressure is now applied to the under side of the arm portion l' of the lever l , said arm moving in an upward direction and causing the stud l^3 to pass from one serration a^{11} in the frame-section a' to the next serration, while the arm portion l^2 will move in a downward direction and will thereby remove the post l^4 away from its holding engagement with the edge e^{10} of the lip e^6 of the catch-plate e , as will be clearly evident. Said plate e now being free to slide, a push upon the push-piece h' in the direction of the arrows 2 in Figs. 4 and 5 will force the holding-tongue e^5 on said plate e away from the hook a^7 of the post a^8 , connected with the frame-section a' , and the spring b will immediately actuate said frame-sections a and a' and cause them to fly apart. Without any further manipulation of the levers k and l the plate e and push-piece h' may now be used in the usual manner of locks for purse or bag frames, as has already been stated and as will be clearly evident. To again cause the inoperative arrangement of the catch-plate e , all that is necessary is to move the

levers k and l in opposite directions on their fulcrum supports to cause them to return to their normal or initial positions, (indicated 70 in Figs. 1, 3, and 4,) when the plate e and slide i will once more be held in their normally immovable positions.

The many advantages of my novel construction of purse or bag frame and locking-75 catch are evident from the above description, the construction of the several parts being simple, cheap, and neat, as well as operative, and at the same time providing a toy or puzzle of great utility, from which may be obtained great pleasure and amusement.

I am aware that changes may be made in the several arrangements and combinations of the various parts, as well as in the details of the construction thereof, without departing 85 from the scope of my present invention. Hence I do not limit my invention to the exact arrangements and combinations of the parts as herein shown and described, nor do I limit myself to the exact details of the construction thereof.

Having thus described my invention, what I claim is—

1. In a bag or purse frame, the combination, with a pair of frame-sections, of a pair of pivoted levers, one on the outer side of each frame-section, a catch-plate slidably arranged in one of said frame-sections, and means connected with said levers, adapted to release said catch-plate from its normally inoperative position, substantially as and for the purposes set forth. 95

2. In a bag or purse frame, the combination, with a pair of frame-sections, of a pair of push-pieces on one of said frame-sections, a pair of pivoted levers, one on the outer side of each frame-section, a catch-plate slidably arranged in one of said frame-sections, and means connected with said levers, adapted to release said catch-plate from its normally inoperative position, substantially as and for the purposes set forth. 105

3. In a bag or purse frame, the combination, with a pair of frame-sections, of a pair of spring-actuated push-pieces slidably arranged on one of said frame-sections, a pair of pivoted levers, one on the outer side of each frame-section, a catch-plate slidably arranged in one of said frame-sections, and means connected with said levers, adapted to release said catch-plate from its normally inoperative position, substantially as and for the purposes set forth. 115

4. In a bag or purse frame, the combination, with a pair of frame-sections, of a channeled bar on one of said frame-sections, a spring in said bar, and a pair of push-pieces slidably arranged on said frame-section carrying said bar, having their ends in operative engagement with the respective ends of said spring, a pair of pivoted levers, one on the outer side of each frame-section, a catch-plate slidably arranged in one of said frame-sections, and means connected with said levers, adapted to 130

release said catch-plate from its normally inoperative position, substantially as and for the purposes set forth.

5. In a bag or purse frame, the combination, 5 with a pair of frame-sections, of a channeled bar on one of said frame-sections, a spring in said bar, push-pieces h and h' slidably arranged on said frame-section carrying said bar, having their ends in operative engagement with the respective ends of said spring, a slide i in said frame attached to said push-piece h , and a lip i^2 on said slide, a catch piece or plate e in said frame attached to said push-piece h' , and flanges on said plate e , a 10 pair of pivoted levers, one on the outer side of each frame-section, and posts on one of said levers in holding engagement respectively with said lip on said slide i and one of said flanges on said plate e , and a post on the 15 other lever in engagement with the other flange on said plate e , all adapted to release said plate e from its normally inoperative position, substantially as and for the purposes set forth.
25. 6. In a bag or purse frame, the combination, with a pair of frame-sections, of a channeled bar on one of said frame-sections, a spring in said bar, push-pieces h and h' slidably arranged on said frame-section carrying said 30 bar, having their ends in operative engagement with the respective ends of said spring, a slide in said frame attached to said push-piece h , a catch-plate in said frame attached to said push-piece h' , a pair of pivoted levers, 35 one on the outer side of each frame-section, and posts on one of said levers in holding engagement respectively with said slide and said catch-plate, and a post on the other lever in engagement with said catch-plate, all adapted 40 to release said catch-plate from its normally inoperative position, substantially as and for the purposes set forth.

7. The herein-described bag or purse frame, comprising a pair of pivoted frame-sections a and a' , said section a having openings a^{13} and a^9 , and said section a' having an opening a^{12} and serrations or corrugations a^{11} , a hook-shaped holding-arm a^x on said section a' , a channeled bar on the outer surface of said 45 section a , a pair of push-pieces slidably arranged on said section a , a spring in said bar having its ends in operative engagement with said push-pieces, a slide i on the inner surface of said section a attached to said push-piece h , and a lip i^2 on said slide, a catch piece or plate e in said section a attached to said push-piece h' , and flanges e^6 and e^7 on said plate e , a holding portion e^5 on said plate e with which the hook-shaped arm a^x engages 50 when the frame-sections are closed, a pivotal pin a^8 in said section a , and a pivotal pin a^{10} in said section a' , a lever k pivotally arranged on said pin a^8 , a post k^3 at one end of said lever k extending into and through the opening a^{13} in said section a and engaging with said lip i^2 of said slide i , a post k^4 at the other 55 end of said lever k extending into and through

the opening a^9 in said section a and engaging with the lip e^7 of said catch-plate e , a lever l pivotally arranged on said pin a^{10} , a stud l^3 at 70 one end of said lever in sliding engagement with said serrations or corrugations in the section a' , and a post l^4 at the other end of said lever l extending into and through the opening a^{12} in said section a' and engaging 75 with the lip e^7 of said plate e , all, substantially as and for the purposes set forth.

8. In a bag or purse frame, the combination, with a pair of frame-sections, of a catch-plate e having an arm e^8 , a bent portion e^4 , and 80 a spring-tongue e^5 , secured to one of said frame-sections, and a hook-shaped holding or locking arm on the other frame-section, arranged to engage said tongue e^5 when the frame-sections are closed, and means connected with said plate e for operating the same and disengaging said tongue e^5 and hook-shaped arm, substantially as and for the purposes set forth.

9. In a bag or purse frame, the combination, 90 with a pair of frame-sections, of a catch-plate e having an arm e^8 , a bent portion e^4 , and a spring-tongue e^5 , secured to one of said frame-sections, and a hook-shaped holding or locking arm on the other frame-section, arranged 95 to engage said tongue e^5 when the frame-sections are closed, and means connected with said plate e for operating the same and disengaging said tongue e^5 and hook-shaped arm, consisting, of a spring-actuated slide on the 100 outer side of one of said frame-sections, and a post h^5 on said slide extending through an opening in said frame-section and secured to said plate e , substantially as and for the purposes set forth.

10. In a bag or purse frame, the combination, with a pair of frame-sections a and a' , of an inlay c in said section a , having a shoulder c^6 , an upwardly-extending portion c^7 , and formed with openings c^{11} and c^{12} , said inlay 110 forming with the inner and upper portion of said frame-section, a chamber C , an inlay c' in said frame-section a' , provided with openings c^{13} and c^{14} , a catch-plate slidably arranged in said chamber C , a hook-shaped holding or 115 locking arm on said frame-section a' , extending through said openings c^{14} and c^{12} in the respective inlays and adapted to engage said catch-plate, a pair of pivoted levers, one on the outer side of each frame-section, provided 120 respectively with posts adapted to engage said catch-plate, and the post on one of said levers extending into and through the openings c^{13} and c^{11} in the respective inlays, substantially as and for the purposes set forth.

11. In a bag or purse frame, the combination, with a pair of frame-sections a and a' , of an inlay c in said section a , having a shoulder c^6 , an upwardly-extending portion c^7 , and formed with openings c^{11} and c^{12} , said inlay 130 forming with the inner and upper portion of said frame-section, a chamber C , and supporting-lugs c^8 on said portion c^7 , an inlay c' in said frame-section a' , provided with openings

c¹³ and *c¹⁴*, a catch-plate slidably arranged in said chamber C, a hook-shaped holding or locking arm on said frame-section *a'*, extending through said openings *c¹⁴* and *c¹²* in the respective inlays and adapted to engage said catch-plate, a pair of pivoted levers, one on the outer side of each frame-section, provided respectively with posts adapted to engage said catch-plate, and the post on one of said levers extending into and through the openings *c¹³*

and *c¹¹* in the respective inlays, substantially as and for the purposes set forth.

In testimony that I claim the invention set forth above I have hereunto set my hand this 27th day of February, 1899.

BENNO VOM EIGEN.
